UNITED STATES PATENT OFFICE

160,076

ANTENNA INSULATOR

Burnie M. Craig, Pasadena, Calif., assignor to
Walter L. Schott Co., Beverly Hills, Calif., a
corporation of California

Application February 28, 1950, Serial No. 3,180

Term of patent 14 years

(Cl. D26—1)

To all whom it may concern:

Be it known that I, Burnie M. Craig, a citizen of the United States, residing at Pasadena, county of Los Angeles, and State of California, have invented a new, original, and ornamental Design for an Antenna Insulator, of which the following is a specification, reference being had to the accompanying drawing, forming part thereof.

Figure 1 is a perspective view of an antenna insulator showing my new design;

Figure 2 is a top plan view;

Figure 3 is a bottom plan view;

Figure 4 is an end elevation view; and

Figure 5 is a side elevational view thereof.

I claim:
The ornamental design for an antenna insulator, substantially as shown.

BURNIE M. CRAIG.
